UNITED STATES PATENT OFFICE

SIDNEY CLAIBORNE, OF FORT WORTH, TEXAS, ASSIGNOR, BY MESNE ASSIGNMENTS,
TO FRIGIDAIRE CORPORATION, A CORPORATION OF DELAWARE

REFRIGERATING APPARATUS

Application filed April 30, 1927. Serial No. 187,927.

This invention relates to mechanical refrigeration and particularly to a mechanically refrigerated cooling unit for cooling various types of commercial refrigerator cabinets such as show-case refrigerators.

One object of the invention is to improve the efficiency of the transfer of heat from the air circulating within the cabinet to the refrigerant by preventing the frosting of the metal walls of the cooling unit while at the same time effecting satisfactory refrigeration.

More particularly it is an object of this invention to provide certain improvements in refrigerating apparatus described and claimed in the copending application of Philip M. Bratten, Serial No. 187,929 filed April 30, 1927. One feature of the Bratten apparatus is the use of relatively large air flues surrounded by relatively narrow brine ducts so that heat may be transferred from the circulating air to the refrigerant more rapidly than heretofore. By using relatively large metal surfaces in contact with the circulating air the average temperature of the brine may be higher than in the conventional brine tank; consequently there will be less accumulation of frost upon these surfaces during the active periods of the operation of the refrigerating machine, and the metal surfaces will be refrosted during the idle periods. By providing relatively narrow brine passages between the metal heat transfer surfaces, substantially all of the brine is caused to circulate actively so that heat will be conducted from the metal walls to the refrigerant evaporator more rapidly than heretofore, with the result that the duration of the active period of the machine is reduced.

It is therefore apparent that refrigeration can be obtained more economically than heretofore, because the heat transferring media, the metal walls and the brine, are caused to operate more efficiently, and because the machine is not required to reduce the pressure upon the refrigerant to the low point necessary heretofore, since the average brine temperature is higher.

One object of the present invention is to

minimize the accumulation of frost upon the metal heat-transfer surfaces of the cooling unit during the active period of operation of the refrigerating machine while maintaining the cooling unit in relatively small and compact form. This object is accomplished by providing the brine duct walls with heat absorbing plates or fins projecting into the air flues of the cooling unit. By using such fins, the average temperature of the brine may be even higher than in the Bratten apparatus; consequently there will be substantially no accumulation of frost upon the metal heat-transfer surfaces to hinder the transfer of heat thereto even during the active period of machine operation. Although the heat transfer walls and the fins are maintained at a temperature higher than the freezing point of the moisture which condenses thereon, the temperature of the circulating air will be sufficiently low for satisfactory refrigeration by reason of the presence of the relatively large metallic heat-transfer surfaces maintained free of frost at all times.

Further objects and advantages of the present invention will be apparent from the following description, reference being had to the accompanying drawings, wherein a preferred form of embodiment of the present invention is clearly shown.

In the drawings:

Fig. 1 is a vertical longitudinal sectional view of a show-case refrigerator cabinet equipped with a cooling unit embodying the present invention;

Fig. 2 is a top view partly broken away, of the cooling unit; and

Fig. 3 is a sectional view on the line 3—3 of Fig. 2.

In Fig. 1, 20 designates a cabinet having solid insulating walls 21, 22 and 23 and other insulating walls provided by dead air spaces between a plurality of plates of glass 24 and 25. A partition 26 divides the interior of the cabinet into a cooling compartment 28 and a food or other display compartment 27.

The cooling unit 30 includes a shell brine tank comprising a sheet metal container made of tin-plated copper or galvanized iron

and formed to provide a brine chamber 31 communicating with relatively narrow brine ducts 32, 33, 34, 35 and 36 which surround relatively large air flues 37 and 38.

5 The chamber 31 is provided with a tightly fitting removable cover 39 and encloses a refrigerating unit composed of an evaporator comprising a header or boiler 40 connected with refrigerant ducts 41. One end of the 10 boiler 40 extends through an opening 42 in the outside wall of the chamber 31 and is secured by a flanged collar 43 and a clamping disc 44 forming one end of the boiler. Pipes 46 and 47 conduct refrigerant respectively into and out of the boiler 40. The 15 chamber and ducts should be filled with brine or other low freezing-point liquid up to about one inch below the top of the container and the boiler should not be located 20 too low in the chamber 31, otherwise only the brine at the lower levels will effectively circulate and be cooled. Preferably the top of the boiler should be about one inch below the level of the brine. It has been found that 25 with a cooling coil located low in a deep tank, the brine above the coil does not cool down to the temperature desired, since it remains above the freezing point even when the rest of the brine may be at or below 30 freezing temperature.

The unit 30 is supported above the bottom of the cooling chamber 28 and is spaced from the chamber walls and baffle 26 so that air may circulate freely around the unit as 35 well as through its flues. The combined surface of the exposed vertical walls of the unit should at least be equal to the exposed surface of the block of ice which would be required to cool the cabinet. By providing 40 relatively narrow brine ducts and relatively large flue openings, a relatively greater exposed area may easily be provided by a cooling unit which will occupy a smaller space than the ice block. The space required by 45 the unit need be no more than approximately two-thirds of the cubical content of the cooling chamber 28, and may be slightly less if necessary to provide at least three inches of space between the walls of the unit and the 50 cooling chamber walls so that air may circulate freely about and through the unit. The matter of clearance is important, because frosting of the tank and ducts tends to decrease the clearance and might even close 55 it off entirely, preventing free circulation of the air. Unless the air can circulate freely adjacent the walls of the cooling unit, it can not absorb the heat from the air. For the same reason the flue openings should be 60 at least four inches in width. If the tank and ducts are made of sheet metal sufficiently thin to permit making the joints by lock-seaming and soldering, the width of the ducts need be only one inch. If heavier sheet 65 material is required on account of the size of

the cooling unit, and the joints must therefore be riveted, the ducts may be two inches wide to allow for introducing riveting tools between the metal sheets forming the ducts. There is no object in making the ducts wider than one inch except to facilitate manufacture. Generally, the brine ducts should be from about one to two inches wide and the flues preferably at least four times as wide as the ducts, although if desired, for some purposes the ducts may be of even less width. 70

The circulation of air within the cabinet is indicated roughly by the arrows 50, 51, 52 and 53. Shelves or other baffles (not shown) may be provided in the food chamber 27 for securing a fairly even distribution of the air circulating therein. 75

If more than one unit is used in a cooling chamber, at least four inches and preferably six inches should be left between the tank for circulation and to prevent the space from being stopped up with frost. 80

One of the features of the Bratten apparatus is the use of such a relatively large metal, heat-absorbing surface adjacent which the air may circulate freely, that it is possible to effect satisfactory refrigeration by brine or other heat transfer medium working at temperatures higher than permissible in brine tanks used heretofore. Although, during the active period of operation of the refrigerating machine frost may collect upon the metal surfaces, these surfaces will be defrosted during the idle periods of the machine. Another feature is the circulation of brine through relatively narrow ducts between the metal heat-absorbing surfaces. Substantially all of the brine which is cooled by the evaporator is caused to circulate actively so that heat will be conducted from the metal walls to the evaporator more rapidly than heretofore, with the result that the duration of the active period of the refrigerating machine is reduced. 90

The present invention solves the problem of preventing the accumulation of frost upon the metal surfaces surrounding the air flues during the operation of the refrigerating machine. The walls surrounding the flues 37 and 38 are provided with metal, heat-absorbing plates or fins 60 and 61 which present a greater total area of metal heat transfer surface to the air circulating through the flues than in the cooling unit disclosed in the Bratten application referred to. These fins are attached in good thermal contact to the walls of the flues and the opposing rows of fins are preferably disposed in staggered or offset relation with respect to each other as shown in Fig. 2 110 in order to secure a better flue effect and to prevent frost from bridging across the fins and thereby impeding the circulation of air. Consequently the temperature of the brine 115 may be maintained above the freezing point 120 125 130

while effecting satisfactory refrigeration. Besides operating as means for transferring heat to the brine, the fins operate as plates upon which the moisture circulating with the air may be condensed without freezing. Since the fins prevent freezing of condensed moisture, the fins may be spaced relatively closely within the flues in order to present the maximum heat transfer area, without danger of obstructing air circulation.

Due to more rapid and more effective circulation of the brine and to keeping the metal surfaces free of frost at all times, the average working temperature of the brine may be higher than heretofore. Therefore the refrigerating machine may be operated more economically since it is not necessary to reduce the pressure upon the refrigerant in the evaporator to that low point required by apparatus in which the working temperature of the brine is lower.

The cooling unit may be provided with horizontal or vertical flues according to the type of refrigerator cabinet with which they are intended to be used. Vertical flues are preferable, owing to the natural tendency of air to descend on being chilled. However, the invention is not limited to cooling units or tanks with vertical flues, as a cooling unit with horizontal flues may be used advantageously in some types of cabinets; for example, a showcase cabinet not provided with a baffle, to separate the food compartment from the cooling compartment.

Where the term "brine" is used in the specification and claims, it refers to any low freezing point liquid or solution which is suitable for transferring heat from the heat transfer walls of the cooling unit to the evaporator.

While the form of embodiment of the present invention as herein disclosed, constitutes a preferred form, it is to be understood that other forms might be adopted, all coming within the scope of the claims which follow.

What is claimed is as follows:

1. Refrigerating apparatus comprising a shell tank having thermally conducting walls of relatively great area, air flues bounded by said walls, a refrigerating medium in said tank, ducts adapted to circulate a relatively small amount of refrigerating medium in contact with said walls, and thermally conducting fins extending from said walls into said flues in contact with air circulating adjacent said ducts, the total area of the walls and fins being adapted to reduce the circulating air to the desired temperature and to maintain the temperature of the fins above the freezing point of the moisture condensed thereon.

2. Refrigerating apparatus comprising a shell tank having thermally conducting walls of relatively great area, air flues

bounded and formed by said walls, a refrigerating medium in said tank, a chamber within said tank adapted to contain refrigerating medium and a refrigerating unit, ducts adapted to circulate a relatively small amount of said refrigerating medium in contact with said walls and thermally conducting fins extending from said walls into said flues in contact with air circulating adjacent said ducts, the total area of said walls and fins being adapted to reduce the circulating air to the desired temperature and to maintain the temperature of the fins above the freezing point of the moisture condensed thereon.

3. In a device of the character described a relatively narrow brine duct shaped to form an air flue of relatively large opening, fins extending within said flue, said fins being attached to the duct walls enclosing and forming said flue.

4. In a device of the character described a relatively narrow brine duct shaped to form an air flue of relatively large opening, rows of fins extending within said flue, said fins being attached to the duct walls enclosing and forming said flue, the fins of one row being disposed in off-set relation with respect to the fins of the opposing row.

5. Apparatus according to claim 1 including a relatively narrow brine duct enclosing and forming a flue of relatively large opening, fins extending within the flue and attached to the duct walls enclosing said flue, the flue being greater in width than the width of the brine duct.

6. Apparatus according to claim 1 including a relatively narrow brine duct enclosing and forming a flue of relatively large opening, fins extending within the flue and attached to the duct walls enclosing said flue, said brine duct being substantially from one to two inches wide and the flue at least four times the width of said brine duct.

7. A shell brine tank composed of substantially parallel walls spaced to form brine-carrying ducts, a brine chamber in said tank, brine cooling means in said chamber, air flues formed in said tank by said brine-carrying ducts and fins on the walls of said ducts extending into said flues.

8. A shell brine tank composed of substantially parallel walls spaced to form brine-carrying ducts, a brine chamber in said tank, brine cooling means in said chamber, air flues formed in said tank by said brine-carrying ducts and fins in the walls of said ducts extending into said flues, said ducts being appreciably smaller in width than said air flues.

9. A refrigerating device, comprising a shell tank comprising hollow walls adapted to form a narrow chamber and adapted to contain a refrigerating medium, said walls being arranged to form a flue, and a heat

absorbing member in thermal contact with a wall of said tank and extending into said flue.

10. In a refrigerating device, a shell tank comprising a plurality of vertically extending hollow walls to form a chamber adapted to contain refrigerating medium, said walls being arranged to form a vertically extending flue, and a vertically extending heat absorbing member in thermal contact with a wall of said tank and extending into said flue.

In testimony whereof I hereto affix my signature.
